D. S. MULLIN

STEAM SHOVEL MECHANISM

Filed Nov. 1, 1921

INVENTOR
Donald S. Mullin,
by Edward A. Lawrence,
his attorney.

UNITED STATES PATENT OFFICE.

DONALD S. MULLIN, OF STATE COLLEGE BOROUGH, PENNSYLVANIA, ASSIGNOR OF ONE-HALF TO ROBERT SWAN, JR., OF PITTSBURGH, PENNSYLVANIA.

STEAM-SHOVEL MECHANISM.

Application filed November 1, 1921. Serial No. 512,124.

To all whom it may concern:

Be it known that I, DONALD S. MULLIN, a citizen of the United States, and residing in the borough of State College, in the county of Center and State of Pennsylvania, have invented or discovered the new, useful, and Improved Steam-Shovel Mechanism, of which the following is a specification.

10 My invention consists in new and improved releasing means for the bottoms of steam shovel scoops.

In the present practice the scoop bottom is unlatched or released, to dump the load, 15 by means of a pull rope which the operator grasps and pulls at the proper moment; but as the operator usually requires both hands to operate the various control levers of the steam shovel, this method forces him to 20 take his hand from one of said levers when he desires to reach for the release rope. This is inconvenient and often perilous.

The object which I have in view is the provision of means whereby the scoop bottom 25 may be released by the operator without his taking either of his hands from the control.

I obtain this advantageous result by connecting the pull rope to power-operated 30 means which are controlled from one of the said control levers but in such a manner as not to interfere with the main or original functions of the said lever.

Thus, in the embodiment of the principles of my invention shown in the accompanying drawings, I show the pull rope operated by means of a fluid pressure or steam cylinder to which power is admitted by a valve controlled by one of the main 40 control levers of the steam shovel, said main control lever being so modified that the operator may, with one hand on the lever, cause it to accomplish not only its main functions in the usual manner but may also, without affecting said main functions, 45 release the scoop bottom whenever it is desired to dump the load.

I also provide new and improved fluid pressure means for releasing the bottom, said means being shown controlled from one of the main control levers of the steam shovel, as aforesaid.

I also show a new and improved fluid pressure admission and relief valve mechanism for said fluid pressure means.

Other novel features of construction and arrangement of parts will appear from the following description.

In the accompanying drawings, which are however merely intended to be illustrative of the principles of my invention without limiting the scope of the same to the construction shown, Fig. 1 is a side elevation of a steam shovel to which an embodiment of my invention is applied; Fig. 2 is 65 an enlarged sectional detail showing the steam cylinder which operates the pull rope, and its associated parts; Fig. 3 is a detail of the steam valve and its control, and Fig. 4 is an enlarged detail, with the boom shown in section, illustrating the housing for the sliding multiple block over which the pull rope runs.

The following is a detailed description of the drawings:

A represents the cab of the steam shovel, rotatably mounted in the usual way on the truck B.

C represents the mast pivoted at its foot on a horizontal axis. D represents the 80 crowding boom both swingingly and slidably mounted on the mast C. E represents the bucket or scoop pivotably mounted on the end of the boom and controlled in the usual manner from the cab. I have simply indicated these parts without showing the means for operating the same, as they are familiar to those skilled in the art and in themselves form no part of the present invention.

The operation of the same however is controlled in the usual manner by levers in the cab which the engineer grasps when operating the machine. I have indicated one of said levers at F, it being immaterial 95 which one of the said control levers is selected for my purpose.

G represents the bottom of the scoop E, the same being hinged to the scoop and normally held in its closed position by the sliding latch or bolt 1 which is connected by the chain 2 to an intermediate point on the lever 3 whose one end is pivoted to the boom D while its other end is attached to the pull rope 4, so that a tug on said rope 105 will release the latch 1 and permit the bottom to drop and dump the load.

The rope 4 is run around the pair of triple or multiple blocks H and I, the end of said rope being attached to one of said 110

blocks, such as to the block H at 5. The block H is journaled in a fixed position at the side of the mast, as by the bracket 6, while the block I is mounted to slide between the two guides 7 attached to the side of the mast. Said block I is mounted on the protruding end of the piston rod 8 attached to the piston 9 of the single-acting steam cylinder J mounted on the side of the mast. 10 is a helical spring coiled about the piston rod 8 between the block I and the head of the cylinder J thereby tending to slack the pull rope 4 and permit the bottom G to close and latch.

15 The forward end of said cylinder J is provided with a port 11 communicating with valve chamber K having an inlet port 12 and a smaller outlet port 13. 14 is a rocking lever in said chamber pivotally supported intermediate of its ends on a depending post or bracket 15. One end of said lever is provided with a valve 16 adapted to close the inlet port 12, while the other end of said lever is provided with a valve 17 adapted to close the outlet port 13. A helical spring 18 normally holds the lever in position to close the inlet port and open the outlet port. 19 is a steam pipe connected to the inlet port 12 and leading down along the mast C to a flexible joint 20 axially aligned with the pivotal axis of said mast; and 21 is a pipe in the cab and connecting said joint to the boiler or main steam supply. 22 is a slide valve interposed in the pipe 21 having its plug 23 attached by a loose pivot connection to the lower end of the bell crank lever 24 having its apex pivotally mounted on the front wall of the cab while its upper end is connected by the link 25 to the projecting arm 26 rigidly attached to the hand grip 27 of the said control lever F. The said hand grip 27 is pivotally connected to the upper end of the lever F in such a manner as to be tiltable in relation to the lever in one direction and that at substantially right angles to the path in which the lever is moved in performing its main control functions. The pivotal connection between the upper end of the bell crank lever 24 and the lower end of the link 25 is horizontally aligned with the axis of the swinging movement of the lever F so that the swinging of the lever F will not affect the bell crank lever or operate the valve 22 but should the operator by a twist of his wrist throw the hand grip 27 to the left in Fig. 3, it is evident that the valve 22 will be opened to an extent governed by the degree in which the grip is thrown over, and, vice versa, the swinging of said grip back into the position shown, in alinement with the lever F, will result in closing said valve. I have shown the grip adapted to be swung down toward the left as the same is preferable in the case of a lever worked with the

right hand of the operator, but if the steam valve 22 is to be operated in connection with a left hand lever, the grip would preferably be arranged to swing toward the right.

When steam is admitted to the pipe 19 by opening the valve 22, it automatically forces open the inlet valve 16, by compressing the spring 18, and closes the outlet valve 17. The steam enters the port 11, causing the piston 9 to retreat in the cylinder J thus separating the blocks H and I, and, by shortening the pull rope, unlatching the scoop bottom. When the valve 22 is closed, the pressure falls in the pipe 19, permitting the spring 18 to close the inlet port 12 and open the outlet port 13, thus relieving the pressure in front of the piston 9 and thus permitting the spring 10 to move the block I toward the stationary block H, thus lengthening the pull rope and permitting the bottom to close and latch. A weight 28 is provided to insure against the rope slackening between the blocks H and I as they approach.

The amount of slack required to be taken up in the pull rope before the latch is released, of course, varies with the position of the dipper relative to the mast, but this is taken care of by the shock absorbing tendency of the rope, as well as by the operator by regulating the amount of steam which is admitted to the cylinder J and consequently the distance which the piston 9 is caused to retreat in the cylinder.

The relief port 13 of the valve chamber K is preferably connected by a pipe 30 with the main steam exhaust pipe of the steam shovel which usually extends to the top of the mast C.

It is evident from the foregoing that my invention greatly improves and facilitates the control of the operation of the steam shovel, as the same not only renders such operation more convenient, but it enables the contents of the scoop to be accurately placed when dumped.

What I desire to claim is:—

1. In combination with a steam shovel provided with a swinging hand lever to control the operation of the same and having a scoop with a hinged bottom and a latch to hold said bottom closed, a fluid pressure cylinder and piston, a steam pipe leading into said cylinder mounted on a mast, an operative connection between said latch and said piston consisting of a lever mounted on a boom and having connection with the latch, a bracket on the mast, a block journaled on said bracket, a rope on said block, said rope being connected at one end to said last mentioned lever, guides on the mast, a block slideable in said guides and being connected to the piston, said rope being connected at its other end to said slideable block, a hand grip pivoted to the hand lever to control

admission of steam from the steam pipe against the piston to operate said operative connection to release said latch and thereby dump the contents of the scoop.

- 5 2. In combination with a steam shovel provided with a swinging hand lever for controlling the operation of the same and having a scoop with a hinged bottom and a latch to hold said bottom closed, a fluid 10 pressure cylinder and piston on a mast, a steam pipe leading into said cylinder, an operative connection between said latch and said piston consisting of a flexible member carried by a boom and the mast, guides on

the mast, a slidable block in the guides 15 having connection with the flexible member, a spring on the piston rod between the slid- able block and the cylinder for operating the piston to allow the latch to return to operative position and means mounted on 20 the lever to control admission of steam from the steam pipe against the piston to operate said operative connection to release the latch and thereby dump the contents of the scoop.

Signed at State College, Pa., this 25th 25 day of July, 1921.

DONALD S. MULLIN.
